CORRUGATED CARTON HANDLE FORMING MACHINE

Joseph E. McNamara, Detroit, Mich.

Application April 18, 1955, Serial No. 501,921

4 Claims. (Cl. 164—43)

This invention relates to a machine for lancing or forming handle portions in corrugated cartons.

Handle forming machines and devices have been employed heretofore to facilitate forming handle portions in corrugated cartons to provide the user a convenient hand-hold relative thereto, however, the several devices and machines of the prior art have not proven entirely satisfactory inasmuch as they are complicated in design and construction, expensive to manufacture, difficult to use, and are usually integrated in the machine which originally forms the corrugated carton or box thereby precluding their subsequent use on cartons already made.

With the foregoing in view, the primary object of the invention is to provide a handle cutting or forming machine or device which is simple in design and construction, inexpensive to manufacture, easy to use, safe to use, easy to store and transport, and which is available for making handles on already fabricated cartons.

An object of the invention is to provide a corrugated carton handle forming machine which can be manufactured inexpensively as the component parts are easily made and the assembly of parts readily accomplished.

An object of the invention is to provide a handle forming device which can be operated with ease and safety by an unskilled or an inexperienced person.

An object of the invention is to provide a corrugated carton handle forming device which can form single handles or a plurality of handles and in any and all sizes of corrugated cartons without changes in its assembly or arrangement of parts.

An object of the invention is to provide a corrugated carton forming machine which quickly forms the handle portion in the carton and frees the carton from the device so that the carton can readily be removed.

An object of the invention is to supply a corrugated carton handle forming machine so that the cartons and boxes at the super market or neighborhood store can be utilized for carrying out the groceries and/or other provisions instead of necessitating that these cartons be dismantled and shipped out at the store thereby not only saving the cost of dismantling and shipping out, but also the cost of the heavy kraft paper bags of the extremely large size now presently being used.

An object of the invention is to provide a corrugated handle forming machine which quickly and easily forms handle portions in the corrugated carton thereby converting the otherwise objectionable corrugated carton into a desirable, easily handled container for the customer to transport his groceries or other provisions to his vehicle.

These and other objects of the invention will become apparent by reference to the following description of a corrugated carton handle forming machine or device embodying the invention taken in connection with the accompanying drawings in which:

Fig. 1 is a longitudinal vertical cross-sectional view of the inventive device in the open position showing a corrugated carton portion disposed therein.

2

Fig. 2 is a view similar to Fig. 1 showing the inventive device in the closed position with the handle portion lanced out and crimped for folding back in the corrugated carton portion.

Fig. 3 is a longitudinal horizontal cross-sectional view of the device taken on the line 3—3 of Fig. 2.

Fig. 4 is a cross-sectional view of the device taken on the line 4—4 of Fig. 2.

Fig. 5 is a cross-sectional view of the device taken on the line 5—5 of Fig. 2.

Fig. 6 is a perspective view of a corrugated carton portion with the handle formed therein.

Fig. 7 is a cross-sectional view of Fig. 6 taken on the line 7—7 thereof; and

Fig. 8 is a view similar to Fig. 7 with the lap portion of the handle folded back in the use position.

Referring now to the drawings wherein like numerals refer to like and corresponding parts throughout the several views, the corrugated carton handle forming machine or device disclosed therein to illustrate the invention comprises a frame assembly 10 adapted to rest on a floor or other support, a head assembly 11 mounted on the frame 10 adapted to support the upper shearing and crimping portions of the device in spaced relationship to the frame 10, and a lower jaw linkage assembly 12 pivotally mounted on the frame 10 adapted to support the lower shearing and crimping portions so as to cooperate with the head assembly 11.

More particularly, the frame assembly comprises spaced parallel vertical side plates 14 and 15 adapted to rest on their lower edges 17 and 16 which are interconnected at their front ends 18 and 19 by a cross member 20 and at their rear ends 22 and 23 by a cross member 21 adjacent so that the plates 14 and 15 are maintained in rigid relationship to one another.

The plates 14 and 15 are equipped with paired neck portions 24 and 25 rising above the general area of the plates intermediate the ends thereof and the head portion plate 26 is mounted on the neck portions 24 and 25 which plate 26 is equipped with a cantilevered portion extending toward the front ends 18 and 19 of the plates in spaced relationship to the plate top edges 28 and 29 so as to form a carton portion receiving mouth therebetween and it is to be noted that the forwardly cantilevered portion of the head plate 26 is equipped with an opening defined by a front shearing edge 30, side shearing edges 31 and 32, and a rear crimping edge 33 and that a resilient member 34 is disposed in the opening area as defined by the edges so as to be capable of urging the corrugated carton cut-out portion downwardly outwardly of the opening. The cover plate 90 is disposed in spaced relationship to the head 26 and forms a receiving chamber therebetween for receiving the cutting edges of the lower jaw teeth.

The lower jaw assembly 12 comprises paired lower jaw arms 35 and 36 pivotally mounted as at 37 and 38 on the side plates 14 and 15 and these jaw arms extend forwardly into the area of the opening in the head plate 16. The jaw plate 39 interconnects the jaw arms 35 and 36 at the forward end while the front shearing tooth 40, the side shearing teeth 41 and 42, and the rear crimping tooth 43, are mounted on the plate 39 and the jaw plate 39 and the teeth 40—43 are indexed and adapted to co-operate with the shearing edges 30, 31 and 32, together with the crimping edge 33 defining the opening in the head plate 26 upon the upward movement of the jaw plate 39.

Paired lever supporting arms 44 and 45 are mounted on the plates 14 and 15 and depend and project into the interior area of the frame assembly 10 and are pivotally connected as at 46 and 47 to the paired lever arms 48

and 49 whose forward ends 50 and 51 are disposed beneath the jaw plate 39 and whose rearward ends 52 and 53 are interconnected by the foot pad or hand pad 54 so that when the foot pad 54 is depressed from the position seen in Fig. 1 to the position seen in Fig. 2, the lever ends 50 and 51 lift the jaw plate 39 upwardly so as to pass the teeth 40-43 past the shearing edges 30-33 so as to lance through the carton portion 60 on three sides and to crimp the carton portion 60 at the fourth side so that the imperforate carton portion 60, as seen in Fig. 1, is converted to a perforate portion as seen in Figs. 2 and 6-8 whereby the handle portion is formed in the carton wall.

It is to be noted that when the jaw plate 39 and teeth mounted thereon move from the canted position seen in Fig. 1 that tooth members 40-43 move arcuately relative to the pivot points 37 and 38 past the shearing edges 30-32 so as to shear and bite through the carton in a shearing action in that the teeth move from the inclined or canted position of Fig. 1 arcuately to the straight line upright position as seen in Fig. 2 with the resilient member 34 depressing the lanced out portion 61 of the handle formed portion of the carton area 60 so that the crimping tooth 43 abuts the bottom of the plate 26 at the edge 33 in non-shearing relationship so that the tooth 43 is capable of scoring the carton portion at 62, Fig. 7, so that the partially or three sided lanced-out portion 63 can be folded back by the user from the position seen in Fig. 7 to that of Fig. 8 whereby the crimped portion 62 acts as a pivot or hinge area for the lanced-out portion 63. A wide arcuate smooth area 64 via the fold back of the lanced-out portion 63 is formed whereby the user can grip the carton at a smooth large area thereby eliminating sharp cutting edges on the carton relative to the holder's hands the contact between the crimping tooth 43 and the bottom of the plate 26 also acts as a stop preventing further travel of the shearing edges and further travel of the actuating levers.

Due to the fact that the paired arms 44 and 45 form the back of the mouth area, it is to be noted that the carton portion 60 cannot be inserted therewith so that the lanced-out handle portion is always regularly spaced relative to the top of the carton for easily handling and proper balance.

Two springs are shown in the drawings, namely spring 65 and spring 66, which are connected to the jaw cross plate 67 and to the jaw plate 39 and these two springs are provided to provide an initial downward urge such as by the spring 65 from the position seen in Fig. 2 to that of Fig. 1 and the spring 66 is provided for the later movement after the initial urging by the spring 65.

Obviously other spring means such as a leaf spring urging the jaw linkage assembly to the inactive position can be employed or a weight can be used to urge the jaw linkage assembly to the open position, however, it has been found that the instant spring assembly, as shown, is adequate to draw the teeth out of the carton and leave the carton free for removal from the device after the handle has been formed in the carton.

In use, the user takes the edge of a carton and inserts it into the device, Fig. 1, until the top thereof abuts the arms 44 and 45 or another stop, the operator then places his foot on the pad 54 depressing same so as to cause the front ends 50 and 51 of the lever arms to move upwardly under the jaw plate 39 as to urge the teeth 40-43 upwardly so as to carry the carton portions 60 against the head plate 26 whereby the teeth shear against the edges 30-33 and lance areas 70, 71, and 72 through the carton forming bottom and side portions of the handle area and to crimp or score an area 73 forming the top or handle holding area such as designated by the numeral 64 of Fig. 8. Upon the handle opening being so formed, the user lifts his foot from the pad 54 and the springs 65 and 66 return the device to the position seen in Fig. 1 with the resilient members 34 preventing the tab lanced portion 63 from entering the head opening so that a carton is

free for removal. The user then turns the carton completely over and lances another handle aperture on the other side and the carton is then ready for use as a container with easily used handle portions.

5 The inventive handle forming device or machine particularly suitable for corrugated cartons and boxes with the features described constitutes a compact, durable, neat appearing mechanism, easily and quickly operated to form handle apertures in corrugated boxes and cartons so that 10 not only are useful handles formed but handles are formed with a professional or manufactured appearance as attractive as though much laborious time has been consumed in forming the handles.

It is to be particularly noted that the tooth 40 is 15 equipped with leading edges 81 and 82 and a lower center portion 83 which follows the initial puncture effected by the leading edges 81 and 82 and that these leading edges lead the side cutting teeth 31 and 32 so that the side cutting teeth take over the shearing of the carton after the leading edges have made the initial puncture. The scoring or crimping edge acts as a stop after the shearing has been accomplished.

Although but a single embodiment of the invention has 20 been shown and described in detail, it is obvious that 25 many changes may be made in the size, shape, detail, and arrangements of the various elements of the invention within the scope of the appended claims. For example, one lever arm and/or one jaw arm could be used.

I claim:

- 30 1. A corrugated carton handle forming machine comprising spaced parallel vertical side plates having lower edges forming a supporting base, a front end, a rear end, upper edges on said plates, means interconnecting said plates adjacent their lower edges, neck portions on said 35 plates intermediate the ends thereof rising above said plates, a head portion disposed between said plate neck portions and cantilevered forward to a point adjacent the front ends of said plates in spaced parallel relationship to said plate's upper edges forming an open carton edge 40 receiving mouth therebetween with the cantilevered portion of said head constituting an upper jaw; said head jaw portion having an opening adjacent the end thereof defined by shearing edges on the front and sides and a crimping edge at the rear; a top plate disposed over said head in spaced relationship relative thereto forming a 45 protective cover over said opening and a receiving chamber therebetween for lower jaw teeth, paired lower jaw arms pivotally mounted on said side plates adjacent the rear thereof and having ends extending forwardly to a point adjacent said head opening, a lower jaw plate intermediate the ends thereof, a lower jaw plate 50 connecting the extending ends of said arms, shearing teeth on said lower jaw plate on the front and sides thereof and a crimping tooth at the rear thereof adapted to co-operate with said head opening corresponding portions; paired lever arms having front and rear ends pivotally mounted intermediate the ends thereof adjacent the front ends thereof; said lever arms front ends being slidably disposed beneath said lower jaw plate; a pad member interconnecting said lever arm rear ends, a spring mounted on 55 said lower jaw adapted to urge said lower jaw and associated linkage out of association with said head to maintain the mouth area normally open, and a resilient member in said head opening area adapted to prevent the lanced and crimped portion of a carton from entering said head opening.
- 60 65 2. A corrugated carton handle forming machine comprising spaced parallel vertical side plates having lower edges forming a supporting base, a front end, a rear end, and upper edges on said plates, means interconnecting said plates adjacent their lower edges, neck portions on said plates intermediate the ends thereof rising above said plates, a head portion disposed between said plate neck portions and cantilevered forward to a point adjacent the front ends of said plates in spaced parallel relationship to said plate's upper edges forming an open carton 65 edge receiving mouth therebetween with the cantilevered

portion of said head constituting an upper jaw; said head jaw portion having an opening adjacent the end thereof defined by shearing edges on the front and sides and a crimping edge at the rear; a top plate disposed over said head in spaced relationship relative thereto forming a protective cover over said opening and a receiving chamber therebetween for lower jaw teeth, paired lower jaw arms pivotally mounted on said side plates adjacent the rear thereof and having ends extending forwardly to a point adjacent said head opening, a lower jaw plate interconnecting the extending ends of said arms, shearing teeth on said lower jaw plate on the front and sides thereof and a crimping tooth at the rear thereof adapted to co-operate with said head opening corresponding portions; paired lever arms having front and rear ends pivotally mounted intermediate the ends thereof adjacent the front ends thereof; said lever arms front ends being slidably disposed beneath said lower jaw plate; a pad member interconnecting said lever arm rear ends, a spring mounted on said lower jaw adapted to urge said lower jaw and associated linkage out of association with said head to maintain the mouth area normally open, and a resilient member in said head opening area adapted to prevent the lanced and crimped portion of a carton from entering said head opening; said shearing teeth on said lower jaw plate being elongated at the leading corners so as to initially pierce the carton portion and then shear out a three-sided tab.

3. A corrugated carton handle forming machine comprising spaced parallel vertical side plates having lower edges forming a supporting base, a front end, a rear end, and upper edges on said plates, means interconnecting said plates adjacent their lower edges, neck portions on said plates intermediate the ends thereof rising above said plates, a head portion disposed between said plate neck portions and cantilevered forward to a point adjacent the front ends of said plates in spaced parallel relationship to said plate's upper edges forming an open carton edge receiving mouth therebetween with the cantilevered portion of said head constituting an upper jaw; said head jaw portion having an opening adjacent the end thereof defined by shearing edges on the front and sides and a crimping edge at the rear; paired lower jaw arms pivotally mounted on said side plates adjacent the rear thereof and having ends extending forwardly to a point adjacent said head opening, a lower jaw plate interconnecting the extending ends of said arms, shearing teeth on said lower jaw plate on the front and sides thereof and a crimping tooth at the rear thereof adapted to co-operate with said head opening corresponding portions; paired lever arms having front and rear ends pivotally mounted intermediate

the ends thereof adjacent the front ends thereof; said lever arms front ends being slidably disposed beneath said lower jaw plate; a pad member interconnecting said lever arm rear ends, a spring mounted on said lower jaw adapted to urge said lower jaw and associated linkage out of association with said head to maintain the mouth area normally open, and a resilient member in said head opening area adapted to prevent the lanced and crimped portion of a carton from entering said head opening.

4. A corrugated carton handle forming machine comprising spaced parallel vertical side plates having lower edges forming a supporting base, a front end, a rear end, and upper edges on said plates, means interconnecting said plates adjacent their lower edges, neck portions on said plates intermediate the ends thereof rising above said plates, a head portion disposed between said plate neck portions and cantilevered forward to a point adjacent the front ends of said plates in spaced parallel relationship to said plate's adjacent upper edges forming an open carton edge receiving mouth therebetween with the cantilevered portion of said head constituting an upper jaw; said head jaw portion having an opening adjacent the end thereof defined by shearing edges on the front and sides and a stop constituting a crimping edge at the rear; paired lower jaw arms pivotally mounted on said side plates adjacent the rear thereof and having ends extending forwardly to a point adjacent said head opening, a lower jaw plate interconnecting the extending ends of said arms, shearing teeth on said lower jaw plate on the front and sides thereof and a crimping tooth at the rear thereof adapted to co-operate with said head opening corresponding portions; paired lever arms having front and rear ends pivotally mounted intermediate the ends thereof adjacent the front ends thereof; said lever arms front ends being slidably disposed beneath said lower jaw plate; a spring mounted on said lower jaw adapted to urge said lower jaw and associated linkage out of association with said head to maintain the mouth area normally open.
